(57) **CLAIM**

The ornamental design for a urination shield/catch basin for a commode seat, as shown and described.

DESCRIPTION

FIG. 1 is a perspective view showing my new design for a urine shield/catch basin for a commode.

FIG. 2 is a top plan view of the urination shield/catch basin for a commode seat..

FIG. 3 is a back view of the urination shield/catch basin for a commode seat..

FIG. 4 is a side view of the urination shield/catch basin for a commode seat; and,

FIG. 5 is a perspective view showing my new design for a urination shield/catch basin for a commode seat in a mounted position on a conventional commode.

The broken line showing of the commode in FIG. 5 is for illustrative purposes only and forms no part of the claimed design.
